APPLIANCE

Harold Cohen, Elizabeth, N. J.

Application January 23, 1945, Serial No. 574,092

3 Claims. (Cl. 248—230)

1

This invention relates to an appliance which may be used advantageously to support a hoist on parts of a structure in the course of erection, so as to enable the hoisting of the structural components and other materials to be used in the erection of the structure, such as a tower, framework and the like.

The principal object of the invention is the provision of improvements in a device of the indicated character, whereby a hoist or the like may be supported or mounted or put into position for use, and also be shifted from one position of use to another, quickly and easily.

With the foregoing, other objects of the invention will appear in conjunction with the combination, construction and function of the parts hereinafter described and illustrated in the accompanying drawing, in which—

Fig. 1 is a side elevational view of a hoist attached for use in accordance with the invention, to parts of a tower in the course of erection, by way of example.

Fig. 2 is an enlarged side elevational view of the hoist detached, portions of the standard being broken away.

Fig. 3 is a sectional view taken on the line 3—3 of Fig. 1, parts of the tower being shown in dot-and-dash lines.

Fig. 4 is an enlarged sectional view on the line 4—4 of Fig. 5, the clamp being shown engaged in full lines, and the hinged part of the clamp being shown open in dotted lines.

Fig. 5 is a side view of the lower hoist supporting device applied to parts of a tower, portions of the device being broken away, and the parts of the tower being shown in dotted lines.

Fig. 6 is a sectional view taken on the line 6—6 of Fig. 5.

A hoist or boom 10 shown most clearly in Fig. 2 is selected to illustrate the use of the present invention. The hoist comprises a standard or mast 11 whose upper end portion is arcuate or curved as at 12. The standard 11 is constructed of cross-sectionally round tubing. The standard may be extensible as to length, or it may be made non-extensible. The upper end portion of the standard has pulleys 13 mounted thereon to accommodate a hoisting cable 14 for carrying out the hoisting and lowering of the structural components and other materials to be used in the erection of a structure, such as a tower. Sections of a tower already assembled are designated 15 and appear in Fig. 1. The hoist is attached to certain of the sections 15 for use, and is capable of being shifted from the position of

2

use shown, upwardly, to another position in the course of the erection of the tower to the required height.

The hoist is detachably supported or mounted in position for use by a plurality of appliances or devices 16 of the present invention which are similar except in one respect to be explained hereinafter.

The device comprises a bearing member 17 and a clamp 18 on said bearing member. The member 17 consists of sleeve. The clamp 18 comprises jaws 19 and 20 respectively. Each of the jaws is approximately semi-circular. The jaw 19 is fixed to the sleeve 17, as by welding, and extends radially therefrom. The jaw 20 is hingedly connected with the jaw 19 by means of eyes 21 on the jaws, respectively, and a pintle 22 which extends through said eyes 21. The jaw 20 has a lateral extension 23. A slot 24 in the extension accommodates a screw stud 25 on the outside of the sleeve 17 and projecting radially therefrom. A wing-nut 26 cooperates with the stud 25 and the extension 23 to retain the jaw 20 in a closed or clamping relation to the jaw 19. The jaw 19 has a depending offset portion 27 which is provided by reason of a semi-circular piece of metal welded to the jaw or the jaw 19 may be of cast in one piece to provide the offset portion 27. This offset portion has spaced notches 28 therein opening downwardly through the lower edge thereof.

The sleeve 17 of each device 16 is designed and adapted to loosely surround the mast 11. The clamp 18 is designed and adapted to engage a vertical component or upright 29 of a section 15 heretofore mentioned, while the offset portion 27 engages two other components or horizontal braces 30 of a section 15, by reason of the notches 28 which receive said braces 30 respectively, as shown most clearly in Figs. 3, 4 and 5.

The hinged jaw 20 of the clamp 18 may be opened as shown in dotted lines in Fig. 4. The clamp then may be brought into position with respect to the upright 29. The jaw 20 is then closed about the upright 29 after which the wing-nut 26 is applied to the stud 25 to securely clamp the device 16. It is understood the jaw 19 of the clamp will be brought down to a position in which the braces 30 are in the notches 28. Thus the mast 11 of the hoist is turnably engaged with the devices 16.

The one respect in which the devices 16 differ is in the provision of an abutment 31 on the sleeve 17 of one of the devices 16. The device with such abutment is used at the lower end of the mast 11. The abutment is in the form of a disk of metal

welded or otherwise secured to the sleeve 17 to serve as a base. The abutment has a central hole 32 therein to receive a screw bolt 33 carried by a dished anti-friction plate 34 welded or otherwise secured to the lower end edge of the mast 11, as shown in Fig. 5. The bolt 33 is loosely received in the hole 32 and keeps the mast 11 from moving upwardly. The abutment 31 sustains the weight of the hoist and any load carried by the hoist.

If desired, collars 35 and 36 may be secured to the mast in proximity to the upper and lower ends respectively of the upper device 16 or the device which does not have an abutment 31. The collar 35 may be made to rest directly upon the upper end of the sleeve 17 in order to help in sustaining the weight of the hoist and its load. The collar 36 may be used to help the bolt 33 in keeping the mast from moving upwardly.

From the foregoing, it will be apparent that the devices 16 enable the hoist to be attached for use quickly and easily; that the hoist may be shifted upwardly or downwardly as the occasions require; that the notched offset portion 27 may be engaged with cross braces by the mere act of letting the hoist down; that the offset portion 27 prevents the devices 16 from turning with respect to the structure being erected; and that the hoist may

be turned in the sleeves 17, or in other words, the hoist may be turned about the axis of the mast 11, to enable the load to be swung over the top of the structure in the course of its erection, thereby facilitating the handling and assembling of the structural elements and other materials used in the construction of a tower or analogous structure.

I claim:

1. An appliance for detachably supporting a standard for turning movement on parts of a fixed structure, said appliance comprising a bearing sleeve adapted to loosely surround the standard, a fixed jaw on the sleeve, a hinged jaw on said fixed jaw cooperating with the latter to engage one of said parts of the fixed structure, means to secure the hinged jaw to the sleeve in functioning position, and means on the fixed jaw to engage other parts of said fixed structure to prevent the appliance from turning with respect to said structure.
- 10 2. An appliance as set forth in claim 1, wherein said last means consists of a notched portion on said fixed jaw.
- 15 3. An appliance as set forth in claim 1, and an abutment on said sleeve which may be engaged by the lower end of said standard.

HAROLD COHEN.
